UNITED STATES PATENT OFFICE.

EDWARD B. PARKHURST AND LOUIS W. WITRY, OF WATERLOO, IOWA, ASSIGNEES TO
THE WATERLOO GASOLINE ENGINE COMPANY, OF WATERLOO, IOWA.

FRICITION-CLUTCH.

1,143,063.

Specification of Letters Patent. Patented June 15, 1915.

Application filed November 14, 1912. Serial No. 731,316.

To all whom it may concern:

Be it known that we, EDWARD B. PARKHURST and LOUIS W. WITRY, citizens of the United States of America, and residents of Waterloo, Blackhawk county, Iowa, have invented certain new and useful Improvements in Friction-Clutches, of which the following is a specification.

Our invention relates to improvements in friction-clutches, and the object of our improvements is to provide convenient and effective means for transmitting rotation from a driving pulley to a driven-shaft, and including means for effectively coupling said parts together for mutual coaction, and other means for conveniently mounting and securing removably the clutch on the driven-shaft.

This object we have accomplished by the means which are hereinafter described and claimed, and which are illustrated by the following drawings, in which:

Figure 1 is an axial vertical section of said friction-clutch as operatively associated with both a driving pulley and with a driven shaft. Fig. 2 is a perspective view of the main sleeve casting of said friction-clutch, with a portion thereof broken away to better disclose its interior bearing surface. Fig. 3 is a vertical transverse section of the neck part of said main sleeve casting, taken on the line *a*—*b* of Fig. 1, looking in the direction of the arrow. Fig. 4 is a greatly diminished left-hand elevation of the structures shown in Fig. 1.

Similar numerals of reference denote corresponding parts throughout the several views.

In the drawings: the reference numerals denote the following described parts. 1 is a driven shaft having an integral or fixed collar 2.

5 is a driving-pulley having spokes 4 and hub 3, the latter loosely mounted on said driven shaft immediately to the right of said collar 2. The hub 3 is projected somewhat to the right and provided with a coned peripheral or circumferential surface on which is movably seated a like inwardly coned ring 15 forming an integral part of the main sleeve casting 16, and said ring has an outwardly directed flange 8 resting against the spokes 4 to its left and having its right-hand surface suitably formed and grooved to act as a seat for the superposed

friction-rings 10, 11, 12 and 13, the rings 10 and 12 having edge projections extending into slots 9 in the rim 41 of an outer and concentric ring 7, the latter having its right-hand part turned inwardly to form a flange 39 which rests upon the right-hand ring 13, and the rings 11 and 13 having projections extending into the grooves 40 of the ring 15 movably. The said rings are therefore held frictionally between the parallel flanged parts 39 and 8 in a well-known manner. Seated upon the extreme right-hand end of the ring 15 is another ring 14 which bears movably against the right-hand face of the flange 39. The middle part of said main sleeve casting 16 has a cylindrical axial opening serving to receive the right-hand end of the driven shaft 1, and has a grooved key-seat 38 adapted to be located opposite a like key-seat in said shaft to contain a key 35.

The casting part 16 is formed with openings 17 extending clear through its opposite parts lengthwise, forming two straight slots connected by a semi-circular slot 37 in the radially-directed part which joins the part 16 to the ring 15. The effect of this slot is to lend a certain small amount of flexibility to the part of the casting 16 thus nearly separated, and this is done to permit the fitting of the part 16 over the shaft 1 and the key 35, since the isolated part will give enough to permit the entrance of said parts into its bearing-cavity, then reacting to hold the parts tightly together, the oppositely placed pairs of lugs 18 being secured together by bolts 19 and nuts 34, which tends to further secure the parts together. When the bolts are loosened or removed, the shaft and its said key 35 may be easily removed, because the isolated half of the part 16 will yield enough to prevent sticking.

The ring 7 has a projection 6 extending to the left far enough to pass between two of the spokes 4 of said driving-pulley and be engaged therewith. This holds the ring 7 in a constant position relatively to said pulley. The other parts 11 and 13 of the clutch, however, may rotate with said pulley only when the ring or annular friction-head 14 is compressed against them, in the following manner and by means of the following-described mechanism.

The numerals 23 and 24 represent fingers

or pawls which are pivoted on the bolts 19 and have their right-hand ends curved toward the axis of the shaft and passed through oppositely-placed slots 26 in the 5 right-hand hollow diminished cylindrical end 25 of said main sleeve casting. Each of said fingers has an outwardly-directed lug 20 orificed parallel to said shaft to receive a set-screw 22 provided with a nut 21, the 10 left-hand end of said screw bearing upon the right-hand face of the ring 14, adjustably. Within the axial hollow of the part 25 of said main sleeve casting, is seated a plunger 27, having two tapers toward the right 15 to form a diminished shank 28 and having a still more diminished end 29, a hand-wheel 30 being seated loosely and slidably on said end 29, and held there by means of a washer 31 and a removable pin 32.

20 When the clutch is in the loose position shown, with the pulley 5 running idly on said shaft 1, the positions of the fingers 23 and 24 are as shown in Fig. 1, with their tips resting upon the diminished part 28 of the 25 plunger-head 27. To shift the ring 14 to the left to tightly compress the said friction-rings together, and thus frictionally connect the shaft 1 to the pulley 5 to be rotated thereby, it is only requisite to pull the plunger-head 27 to the right, the operator grasping the hand-wheel 30, without receiving any injury since the subsequent starting rotation of the parts is not communicated to said wheel. The coned part 27 of said plunger-head is drawn between the tips of the 30 fingers 23 and 24, forcing them apart, and pressing the left-hand ends of the set-screws 22 against the ring 14, the latter then compressing the other friction-rings and effecting 35 a driving communication from said pulley to said shaft. When the plunger-head is pushed back to the left the compression is terminated, and the slippage between the parts breaks the driving communication of 40 the pulley with the shaft.

Having described our invention, what we claim as new, and desire to secure by Letters Patent, is:

1. In combination, a driven-shaft, a driving-pulley loosely mounted thereon, a sleeve mounted on said shaft non-rotatably and having one end extending beyond the end of the shaft and provided at its outer end with an inwardly-extending flange, the projected part of said sleeve having like longitudinal slots on its opposite sides, a plunger seated in the hollow of said projected part, the inner end of the plunger fitting the interior of the sleeve slidably and diminished 50 slopingly and then formed cylindrically to fit slidably in the axial hollow of the contracted end of said sleeve, the outer part of said plunger being diminished beyond said sleeve, arms having like ends pivotally mounted on opposite sides of said sleeve and

having their outer ends curved over toward the shaft and passed through the adjacent slots in the sleeve to lie in the path of movement of the coned part of said plunger, a hand-wheel rotatably mounted on the diminished outer part of said plunger, an annular friction-head mounted coaxially about the said sleeve, said arms adapted to bear against said head when the coned plunger is moved in one direction against the curved ends of the arms, said sleeve having a radial flange, friction-means carried on said sleeve and a member carried slidably by said pulley and adapted to be engaged by said friction-head, friction-means carried movably upon said member, and said member being adapted to frictionally engage said first- and second-mentioned friction-means together and against said radial flange.

2. In combination, a driven-shaft having a fixed annular flange thereon, a driving-pulley rotatably mounted on said shaft near its end and abutting upon the said annular flange, a sleeve mounted non-rotatably on said shaft to project for a distance therebeyond with its outer end contracted to leave a terminal axial orifice of diminished diameter, a plunger mounted in the hollow of said projected part with a diminished end extended through the end orifice of the sleeve, a hand-wheel rotatably mounted on and secured on the diminished part of said plunger, said sleeve having like longitudinal slots on opposite sides, arms pivoted to said sleeve and having their outer ends bent over to pass through said slots, said plunger being adapted when moved in one direction to engage said arms slidingly and push them outwardly, the other end of said sleeve being formed with an outer annular radial flange, friction-rings seated side by side with said flange coaxially, a friction-plate located to abut upon the outermost of said rings and attached removably to said driving-pulley, and a friction-head mounted movably about said sleeve to abut upon said friction-plate, said arms having integral lugs on their outer edges, and set screws seated in said lugs and adapted to have their ends in contact with the last-mentioned friction-ring, to press the latter into engagement with said friction-plate when the arms are pushed outwardly in the sliding action of said plunger, said friction-rings being movably connected in alternation with said sleeve and with said pulley respectively, and being adapted to be compressed upon said radial flange by pressure transmitted from said friction-head.

3. In combination, a driven-shaft, a driving-pulley loosely mounted thereon, a sleeve 125 non-rotatably mounted on said shaft near said pulley and having an offset part provided with an integral outwardly-directed radial flange, the sleeve having longitudinal like openings on opposite sides whose ends 130

extend to said offset part and are placed in communication by a continuing opening in the said part passing half around it, a plurality of contacting friction-plates movably 5 carried on the offset part of said sleeve and abutting upon its flange, and means movably mounted on said sleeve and contacting the outermost of said friction-plates and adapted to be actuated to engage said plates with 10 each other and said flange, one of said fric-

tion-plates being slidably non-rotatably connected to said pulley.

Signed at Waterloo, Iowa, this 26th day of October, 1912.

EDWARD B. PARKHURST.
LOUIS W. WITRY.
